UNITED STATES PATENT OFFICE.

WILLIAM EDGAR McCORMISH, OF NILES, OHIO, ASSIGNOR TO CHARLES HERBERT BOOTH, OF YOUNGSTOWN, OHIO.

DESIGN FOR A TIRE CASING.

Application filed December 7, 1922. Serial No. 4,521. Term of patent 14 years.

To all whom it may concern:

Be it known that I, WILLIAM EDGAR McCORMISH, a citizen of the United States of America, residing at Niles, in the county of Trumbull and State of Ohio, have invented a new and ornamental Design for Tire Casings, of which the following is a specification, reference being had to the accompanying drawings, forming part thereof, in which—

Figure 1 is a plan view of my present design embodied in an automobile tire or casing; and

Figure 2 is a transverse sectional view taken on the line 2—2 of Figure 1.

It is to be understood, however, that my

said ornamental design is applicable not alone to casings, but is intended, and is equally well suited for the ornamentation of other articles of manufacture having surface ornamentation, without in the least departing from my invention.

I claim:

The ornamental design for a tire casing substantially as shown.

In testimony whereof I subscribe my signature in the presence of two witnesses.

WILLIAM EDGAR McCORMISH.

Witnesses:

C. F. GARRISON,
SAMUEL HEINTZ.
